UNITED STATES PATENT OFFICE.

GEORGE J. RATHBUN, OF TOLEDO, OHIO.

GAS-ENGINE ELECTRIC IGNITER.

SPECIFICATION forming part of Letters Patent No. 746,377, dated December 8, 1903.

Application filed May 1, 1903. Serial No. 155,110. (No model.)

To all whom it may concern:

Be it known that I, GEORGE J. RATHBUN, a citizen of the United States, residing at Toledo, in the county of Lucas and State of Ohio,

5 have invented certain new and useful Improvements in Gas-Engine Electric Igniters; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 In internal-combustion engines the most common method of governing is to cut out impulses. This is generally known as the "hit-and-miss" regulation and is economical and entirely satisfactory for ordinary power 20 purposes. When, however, it is desired to operate an electric-light generator, particularly if direct connected, the hit-and-miss method allows too large a variation in the speed, and it becomes desirable to govern by 25 varying the strength of the impulses. This is generally done by throttling the entering combustible mixture.

In an internal-combustion engine it is desirable and necessary for economy that the 30 combustion of the mixture should be complete very near the beginning of the working stroke; otherwise the expansion of the hot working fluid is not as complete as it might be and heat is wasted through the exhaust.

35 In engines of this class the mixture is usually fired by the electric spark. In order that the combustion shall be completed as indicated above, the igniter must be set so as to make a spark in advance, as the inflammation takes 40 an appreciable amount of time for its completion. This time depends upon the temperature and richness of the mass of combustible mixture, and its temperature depends upon the compression-pressure at point

45 of ignition. With a throttling-engine this compression-pressure decreases with the load, due to the fact that the volume of mixture is decreased, but the clearance-space is not changed. It therefore follows that to obtain 50 the best results more time should be allowed for the weak charges to burn—that is, they should be ignited earlier. The present invention

relates to means for controlling this ignition-point automatically to suit each mixture by means of the governor.

The object of my invention is to cause a large saving in gas when the engine is operating on light loads, which is very important, as electric generators must often run one-half or two-thirds of the time at one-third or one-quarter load. I attain these objects by means of the devices and arrangement of parts hereinafter described, and shown and illustrated in the accompanying drawings, in which—

Figure 1 is a front elevation of an upright two-cylinder engine having a chamber for the valve-gears and regulating mechanism with the cover of the chamber removed to show the arrangement of parts hereinafter referred to. Fig. 2 is a side elevation, partly in central vertical section, showing an end view of the shaft carrying the igniter-cam, the rod which actuates the igniter, and the member interposed between the cam and the igniter-rod for automatically varying the point at which the igniter-rod is actuated to operate the igniter, as hereinafter specified; Fig. 3, a top plan view of the same; Fig. 4, a diagrammatic top plan view of the igniter-shaft and its cam, hereinafter referred to, and the variable contact-breaker, hereinafter referred to, illustrating the breaker disposed in different positions in relation to its cam; and Fig. 5, a perspective view of said variable contact-breaker detached.

Like letters and numerals of reference indicate like parts throughout the drawings.

For illustration I have shown in the accompanying drawings a double upright gas-engine, in which the cylinders A are mounted upon a crank-case B, there being at one side of the crank-case a case C for the valve-gear mechanism and the governor. In Fig. 1 the cover of the latter case is removed to show the arrangement of the parts.

1 is a shaft journaled in brackets 1^a, secured to the frame of the engine, carrying a gear-wheel 2, engaged and driven by a "two-to-one" gear-wheel on the crank-shaft of the engine. On the shaft 1 are cams 1^b, arranged to actuate rods 1^c, which control the admission-valves and the exhaust-valves of the engine. On this shaft is also a beveled gear-wheel 3, which engages and drives a beveled

pinion 4 on the lower end of a governor-shaft 5. On this shaft is mounted a governor 6. The governor is connected with and is adapted and arranged to actuate and control rod 7, which regulates the supply of the explosive mixture to the engine. As this feature of the engine constitutes no part of the present invention, it will not be further described, it being understood that any means for regulating the supply of explosive mixture to the engine may be employed.

8 is a sleeve on the governor-shaft, movable longitudinally upon the shaft with the rise and fall of the governor-balls. On this sleeve are 15 two circumferential flanges 9, between which travels a roller 10, mounted on one extremity of a bell-crank lever 11, fulcrumed on the frame of the engine, as at 12. The opposite end of the bell-crank lever engages loosely a 20 block 13, having a screw-threaded opening engaged by a threaded sleeve 14 on rod 15. The sleeve 14 is provided with a set-screw and is movable on the rod 15. By means of the adjustment of the sleeve and of the block 13 accurate adjustment of the rod 15 in relation to the bell-crank lever may be obtained.

The rod 15 is supported in bearings 1^d on brackets 1^a and is movable longitudinally in these bearings. The longitudinal movement 30 of the rod 15 is effected by the throw of the bell-crank lever 11 and the movement of the governor mechanism.

On the shaft 1 is a cam 16, which at each 35 rotation of the shaft is designed to actuate the igniting mechanism of the engine.

17 is a rod commonly known as a "hammer" connected with and which controls the igniter or sparking mechanism of the engine. On the rod 15 is a sleeve 18, from which project 40 arms or rods 19. (See Figs. 2 and 3.) On the rod 15 are collars 18^a, provided with set-screws 18^b 18^c. These set-collars 18^a, one at each end of the sleeve 18, are rigidly secured to the shaft by means of their set-screws, and the rod 15 45 forms a pivot upon which the sleeve 18 and its arms 19 may oscillate or swing between the two set-collars.

20 is a plate or block having therethrough two holes 21, through which pass the arms 19, 50 which form a support for the plate 20. The plate is pressed normally toward the sleeve 18 on the shaft 15 by means of springs 22, the plate resting normally against shoulders 23 on the arms 19. The side of the plate 20 nearest 55 the shaft 1 lies in the path of the cam 16, and the projecting portion of the cam at each revolution comes in contact with the face of the plate 20. This face of the plate 20 is formed with a ledge or margin 20^a, disposed at an angle to the two sides of the plate in such fashion 60 that when the plate is moved with the rod 15 parallel with the shaft 1 the cam 16 will leave the contacting surface of the plate at different points in the rotation of the shaft 1. The 65 point 16^a at which the contacting surface of the cam 16 and the angular portion of the contacting plate leave each other is formed on

exactly the same angle as illustrated in Figs. 3 and 4. The extremity of the rod 17 rests upon the side of the plate opposite the contacting surface. When the cam 16 comes in contact with the angular surface of the plate 20, the plate with its rock-arms 19 and the sleeve 18 swing and lift the rod 17. When the cam passes beyond the margin 20^a of the plate 20, the plate and the rock-arms drop, thereby permitting the rod 17 to fall, thus producing the spark or ignition. It will be seen from an inspection of the drawings that when the engine is running at light load the governor-balls will move the rod 15, carrying with it the sleeve 18 and the plate 20, so that the cam 16 will leave the angular contacting face of the plate 20 almost immediately after the plate is raised by the cam, thus securing an 85 early ignition of the explosive charge. As the load increases and as the speed decreases the plate 20 moves parallel with the shaft 1, bringing the wider contacting portion of the plate 20 into the path of the cam 16, thus securing 90 a later ignition, the time of ignition being exactly in harmony with the relative positions of the cam 16 and the angular contacting portion of the plate 20. The face of the angular margin 20^a is beveled inwardly, as illustrated 95 in Figs. 2 and 5, so that when the cam leaves the sharp edge of the beveled surface 20^a the plate will drop freely and instantly. In case from any cause the engine is turned in the wrong direction the square end of the cam 16 100 comes in contact with the plate 20, which would be broken or torn from its mountings were it not for the extended arms 19 and the springs 22, which permit the plate to slide on the arms before the cam until the cam has 105 passed beyond the plate, when the springs restore the plate to its proper position. Thus it will be seen that no accident can be caused by accidentally turning the engine in the wrong way.

I provide for the adjustment of the ignition-point as follows: One end of the rod 15 is flattened, as at 15^a, (see Fig. 1,) and rests between the jaws 15^b upon the end of a threaded bolt 15^c, which passes through an aperture in cap 15^d, secured to the end of the case C. The outer extremity of the bolt 15^c is formed, as at 15^e, to receive a wrench. On the outwardly-projecting portion of the bolt 15^c is a jam-nut 15^f, by means of which the bolt is rigidly secured in adjusted position. The jam-nut being loosened and a wrench being placed upon the head of the bolt 15^c the rod 15 may be turned, carrying with it its threaded sleeve 14. As the rod 15 is turned it is moved longitudinally in the desired direction by means of the screw-threads on the sleeve 14 and in the block 13, which block is secured to the lower end of the bell-crank lever 11. Thus the position of the angle-plate 20 in relation to the cam 16 and in relation to the governor may be adjusted and controlled from outside the casing of the engine and without stopping the engine.

While I have shown the plate 20 (interposed between the cam and the rod 17) connected with and controlled by the governor, it will be clear to those skilled in the art that if the cam were caused by the governor to move on its shaft and to thus change its relation to the plate 20 the effect upon the time of ignition would be the same. For this reason I do not limit this part of my invention to the exact details of construction here described.

Having described my invention and its operation, what I claim, and desire to secure by Letters Patent, is—

15 1. In an engine of the described class, a governor, an igniter-controlling member, a cam, a plate in the path of the cam and operatively engaged with the igniter-controlling member, a rod upon which the plate is pivotally supported, connections between the rod and the governor by which the rod is moved longitudinally in harmony with the movement of the governor, and an angular contact-face upon said plate adapted and arranged to engage said cam at each revolution.

20 2. In an engine of the described class, a governor, an igniter-controlling member, a cam, a plate in the path of the cam, and operatively engaged with the igniter-controlling member; a rod upon which the plate is pivoted, connections between the rod and the governor by which the rod moves longitudinally in harmony with the movement of the governor, an angular contact-face upon said 25 plate adapted and arranged to engage said cam at each revolution, and means for the lateral adjustment of the plate.

30 3. In an engine of the described class, a governor, a longitudinally-movable rod, an axially-movable sleeve on the rod, arms on the sleeve, a plate mounted to reciprocate on said arms, said plate having an angular contacting surface, a cam which engages said contacting surface at each revolution, an ignition-controlling member which is actuated by

said plate, and a governor which controls the longitudinal position of said rod.

4. In an engine of the described class, a governor, a rod, an axially-movable sleeve on the rod, arms on the sleeve, a plate mounted 50 to reciprocate on said arms, a cam which engages said plate at each revolution, an ignition-controlling member which is actuated by said plate, a governor which controls the longitudinal position of said rod, and means for 55 adjusting the longitudinal position of the rod in relation to the governor.

5. In an engine of the described class, a plate, an igniter-controlling member operatively engaged with the plate, a cam which 60 actuates said plate, supports for the plate which permit the plate to swing outwardly away from the cam when the cam moves in its normal direction and which permits the plate to move before the cam laterally when 65 the motion of the cam is reversed.

6. In an engine of the described class, a governor, a longitudinally-movable rod connected with the governor, an igniter-controlling member, a cam, means upon the rod interposed between the igniter-controlling member and the cam for actuating said member, and means for adjusting the rod in relation to the governor.

7. In an engine of the described class, a 75 governor, a longitudinally-movable rod, a threaded sleeve upon the rod, a nut on the threaded sleeve, a bell-crank lever having one end connected with the governor, its other end being engaged with said nut, means for 80 turning said rod and its sleeve axially, combined with means controlled by said rod for varying the ignition-point of the engine.

In testimony whereof I affix my signature in presence of two witnesses.

GEORGE J. RATHBUN.
